UNITED STATES PATENT OFFICE

141,691

DESIGN FOR A DRAWING SCALE

Verlin C. Miller, Marion, Ind.

Application October 24, 1944, Serial No. 115,949

Term of patent 14 years

(Cl. D52—1)

To all whom it may concern:

Be it known that I, Verlin C. Miller, a citizen of the United States, residing at Marion, in the county of Grant and State of Indiana, have invented a new, original, and ornamental Design for a Drawing Scale, of which the following is a specification, reference being had to the accompanying drawing, forming part thereof.

In the drawing:

Figure 1 is a front elevation of a drawing scale, showing my new design, and

Figure 2 is an edge view taken from the bottom of Fig. 1.

I claim:

The ornamental design for a drawing scale, as shown.

VERLIN C. MILLER.
